BRAKE SHOE

Erik J. Hirvonen, Worcester, Mass., assignor, by
mesne assignments, to Bendix Brake Com-
pany, South Bend, Ind., a Corporation of
Illinois

Original application January 27, 1925, Serial No.
5,129. Divided and this application December
31, 1928. Serial No. 329,521

1 Claim. (Cl. 188—250)

This invention relates to brakes and is illus-
trated as embodied in an internal expanding
brake for the front wheels of an automobile al-
though not limited to such application.

5 One of the objects of the invention is the pro-
vision of a brake shoe of strong yet simple con-
struction that is provided with means by which
it can be pivotally anchored to and has good
bearing on a support and which is also provided
10 with engaging means for a brake-actuating device.

A further object is the provision of a brake
shoe having an arcuate faced body structure
provided with a longitudinally extended strength-
ening rib that has spaced and connected arms
15 at one end for pivotal anchorage to a support
and has a projection at the other end for en-
gagement with a brake applying device.

A further object is generally to improve the
20 construction of brakes and brake shoes.

The present application is a division of my
copending application Serial No. 5,129, filed Jan-
uary 27, 1925.

Fig. 1 is a sectional elevation through an in-
25 ternal expanding brake embodying the present
invention.

Fig. 2 is a section along line 2—2 of Fig. 1.

Fig. 3 is a perspective view of the brake shoe
embodiment of the present invention.

30 Fig. 4 is a section taken along line 4—4 of
Fig. 3.

As here shown the brake includes the rotat-
able drum 10 of any suitable form and a back-
35 ing plate or dust cover 12 which is secured to a
fixed support 14 of any suitable construction.
Three internal expanding brake shoes 16, 18 and
20 respectively are located in the same circum-
ferential line about the inner face of the brake
40 drum and are adapted to be moved outwardly
into frictional engagement therewith. The lower
brake shoe 18 has an arm 22 which extends
upwardly and inwardly from one end thereof
and is pivoted on a stud 24 anchored to the
45 support 14. The other end of said shoe has
spaced ears 26 between which an ear 28 of the
shoe 16 is received. The shoes 18 and 16 are
pivotally connected by the pin 30 which ex-
tends through said ears. The upper end of
50 said shoe 16 has a projection 32 for engage-
ment with a brake-actuating device, here shown

as a cam 34, which is adapted to engage the
end face 36 of said projection to force the shoe
into engagement with the brake drum. The
shoe 16 constitutes a servo shoe which is dragged
down by the rotation of the brake drum into
55 pressure applying relation with the shoe 18,
whereby to force said bottom shoe against the
drum. Said shoe 18 is returned to a normal in-
active position free from the drum, when the
brake setting pressure thereon is removed, by
60 a spring 38 which holds the shoe yieldingly
against an adjustable stop-member 40.

All shoes are provided with friction linings 42.

The shoe 20 which constitutes the main fea-
ture of the present invention consists of a body
structure having an arcuate flange 44 on the face
of which the friction lining is secured. The body
structure is provided with a strengthening rib 46
which is integral with and extends lengthwise of
the arcuate flange 44 in the middle thereof and
upstands from the rear face thereof, thus pro-
viding a body structure which is T-shaped in cross
section, as illustrated in Fig. 4. The free longi-
tudinal edge of said rib is provided with an en-
larged strengthening head 48.

Said rib extends beyond one end of said flange
and is provided thereat with a pair of spaced
projecting portions or arms 50 which are gener-
ally parallel with each other and extend down-
wardly and inwardly of the body-structure of
80 the shoe and have a recess or passage 52 there-
between through which the arm 22 of the shoe
18 is freely extended. The ends of said arms are
integrally connected by a transversely-extended
boss 54 which is located in said passage 52 at the
85 ends of said arms and also extends outwardly be-
yond the outer faces of said arms and is provided
with a transverse aperture or passage 56. Said
boss constitutes a bearing member and is pivoted
on a pin 58 which is fixed to the support 14, there-
90 by pivotally anchoring said shoe to said support.

The rib 46 also is provided with a projection
or extension 60 which projects beyond and in-
wardly of the other end of the arcuate flange 44
and has an enlarged end-section 62 and an end
face 64 which confronts and is adapted to be en-
gaged by the cam 34 to move the shoe outwardly
95 into engagement with the brake drum.

The brake shoe thus described is strong and
rigid in its construction and yet is simple to make,

has a long bearing on its pivotal support, and the supporting arms and projection give good engagement with both the fixed support and the brake actuating mechanism and are well able to withstand the forces which act thereon.

A retractile spring 66 is extended between the upper ends of said shoes 16 and 20 to move them into an inactive position when the brake-apply-
ing pressure thereon is removed.

I claim:

A brake shoe having a body structure and a strengthening rib extended lengthwise thereof which has a pair of spaced arms at one end, and means integrally connecting the ends of said arms. 80

ERIK J. HIRVONEN.
